YARN CARRIER

Ernest A. Feustel, Hasbrouck Heights, N. J.

Application November 13, 1939, Serial No. 304,062

1 Claim. (CL 66—126)

The present invention relates to certain new and useful improvements in yarn carriers, and it relates more particularly to yarn carriers for full-fashioned hosiery knitting machines and the like, wherein the thread is paid out through a replaceable thread-guiding tube which is removably mounted on the yarn carrier.

It has been the practice in the art of full-fashioned hosiery knitting machines to provide yarn carriers or yarn carrier fingers with fine bores at their delivery ends, through which the threads pass as they are being paid out across the needle bank in front of the sinkers, and generally or usually, small-diametered metal tubes are secured to the ends of the yarn carrier fingers, with the passageways inside said tubes constituting the fine-bores through which these threads are paid out. The lower lips of these thread-guiding tubes are crossed by the threads being paid out, usually at an angle of approximately 90°, resulting in substantial wear and grooving at these lower lips, which if unattended to causes damage to the threads passed thereacross and improper feeding of the threads relative to the sinkers. These worn tubes must therefore be frequently replaced with new ones.

The present invention has among its objects the provision of a yarn carrier finger of durable and yet inexpensive construction, having improved means for operatively positioning and releasably retaining a thread-guiding tube at its lower end, said means being readily adapted to be rendered inoperative to permit ready replacement of the tube when worn. Other objects will appear more fully from the following detailed description, accompanying drawing and appended claim.

Referring to the drawing, wherein like reference characters indicate like parts,

Figure 1 represents a perspective view of a yarn carrier finger constituting an illustrative embodiment of the present invention.

Figure 2 represents an enlarged fragmentary view of the underside of the lower end of the finger illustrated in Figure 1.

Figure 3 represents an enlarged longitudinal sectional view taken on line 3—3 of Figure 2, looking in the direction of the arrows.

Figure 4 represents an enlarged transverse sectional view taken on line 4—4 of Figure 2, looking in the direction of the arrows.

Figure 5 represents an enlarged transverse sectional view taken on line 5—5 of Figure 2, looking in the direction of the arrows.

Figure 6 represents an enlarged transverse

sectional view taken on line 6—6 of Figure 2, looking in the direction of the arrows.

In the particular embodiment of the present invention illustrated in the accompanying drawing, the yarn carrier finger indicated generally by the numeral 10 is adapted to be secured to the reciprocable carrier-bar or carriage of the knitting machine. The upper surface of this yarn carrier finger 10 is centrally provided with a smooth thread-guiding groove 11 of gradually increasing depth and width, which extends longitudinally downwardly towards the lower end of finger 10. The lower end of this groove 11 merges with an elongated aperture 12 in the body of finger 10, disposed on a curved zone 13 located near the bottom of the finger 10.

The extreme lower end portion of finger 10 is longitudinally slit at 14, with the upper end of slit 14 communicating with the aperture 12, thereby dividing the lower end portion of finger 10 into two opposed jaws 15, each extending longitudinally from the lowermost edge of finger 10 up to the lower end of groove 11.

As more particularly illustrated in Figure 6, the juxtaposed edges of this slit 14 are preferably cylindrically grooved as at 16, to conform with the exterior surface of a generally cylindrical thread-guiding tube 17 which is operatively gripped between the opposed jaws 15. This tube 17 is frictionally retained between the jaws 15, which are preferably spring-tempered to permit some slight yielding movement when the tube 17 is axially forced downwardly into its operative position between the grooves 16, and also to permit the ready extraction of this tube 17 for replacement purposes without undue difficulty. These jaws 15 preferably exert a sufficiently strong force on the thread-guiding tube 17 to prevent any unintended axial shifting of this tube, particularly in a downward direction.

In order to facilitate the axial entry of tube 17 into the upper end of slit 14, the lower portion 18 of this tube may be slightly tapered to a degree sufficient to permit the lower end of the tube 17 to enter the upper end of slit 14 when the jaws 15 are relaxed. Thereafter, the tube 17 may be forced axially downwardly into slit 14 by any suitable means, as for instance, by means of a pair of pliers, whereupon the advance tapered portion 18 on tube 17 will gradually spread the jaws 15 apart to the required extent, and the tube 17 will be guided into its proper position between the jaws 15.

As more particularly illustrated in Figure 2, the underside of finger 10 bears in the vicinity of

the lower curved portion thereof a relatively extensive shallow recess 19, which overlaps the finger aperture 12 and extends for a substantial distance beyond the outline of said aperture on either side of and above said aperture, thereby providing the surrounding webs 20 and 21.

A curved leaf-spring 22 is seated inside this recess 19, flush with the under-surface of finger 10 on all sides, and generally completely occupying the space defined by said recess. The upper end of this leaf-spring 22 may be secured to the finger 10 in any suitable manner, as for instance by means of the illustrated transversely-spaced rivets 23, which extend through the web 21. In its normal position, the curved leaf-spring 22 may either possess sufficient inherent tension to urge the lower free end of this spring upwardly into intimate contact with the under-surfaces of the webs 20, or, if desired, this curved leaf-spring 22 may merely rest within the recess 19 in a relaxed condition, but with the lower portion of said leaf-spring being curved in conformance with the curved zone 13 on the finger 10 to lie adjacent the webs 20. In either case, however, the lower edge 24 of the leaf-spring 22 in its normal position lies directly over the upper edge of the thread-guiding tube 17 without obstructing the inner bore thereof, all as illustrated in Figures 2, 3 and 5.

In the illustrated embodiment, the leaf-spring 22 bears an aperture 25 which registers with the aperture 12 in the finger 10. This spring aperture 25 serves a dual purpose, firstly, it permits the insertion of any suitable tool or instrument through leaf-spring 22 for flexing the free end thereof outwardly into a non-obstructing position relative to the guide-tube 17, as indicated in dashed-dotted lines in Figure 3, and, secondly, the presence of aperture 25 in the bending axis of leaf-spring 22 renders the lower end of this leaf-spring somewhat more resilient, due to the resultant reduction in metal.

When the lower edge 24 of the leaf-spring 22 is thus flexed into its non-obstructing position relative to the guide-tube 17, the latter may be extracted from between the clamping jaws 15 by being slid axially upwardly out of the slit 14 by any suitable means, as for instance by means of a pair of pliers or the like. A new thread-guiding tube 17 may then be readily operatively positioned intermediate the jaws 15 by inserting its lower tapered portion 18 into the upper end

of the slit 14, causing the free edge 24 of the leaf spring to flex rearwardly, and then forcibly sliding the tube downwardly into the slit 14 by means of a pair of pliers or the like. When the upper edge of this new tube 17 clears the rearwardly flexed lower spring-edge 24, the latter will spring back into its recess 19 and will again obstruct the upper edge of tube 17, thereby acting as an abutment fixing the position of the tube and preventing unintended upward axial shifting thereof.

The present invention may be embodied in other specific forms without departing from the spirit or essential attributes thereof, and it is therefore desired that the present embodiment be considered in all respects as illustrative and not restrictive, reference being had to the appended claim rather than to the foregoing description to indicate the scope of the invention.

Having thus described the invention, what is hereby claimed as new and desired to be secured by Letters Patent is:

In a knitting machine, a thread carrier finger having a relatively long flat body transversely curved near its lower end, an aperture in said body at its curved portion, a longitudinal slit at the lower end of said body extending upwardly to said aperture, a fine-bore thread-guiding tube frictionally retained in said slit and extractable therefrom by axial movement, the tube being of generally uniform outside diameter along a portion thereof extending from within said slit upwardly to the uppermost edge of said tube, a recess on the under-surface of said body at its curved portion and overlapping the aperture in said body, and a curved leaf-spring generally completely contained within said recess and lying generally flush on all sides with the under-surface of said body, with the curvature of said leaf-spring generally conforming with the curvature of said body, the lower edge of said curved leaf-spring normally obstructing the upper edge of said thread-guiding tube and serving as an abutment preventing upward axial movement of said tube, and said lower spring-edge being adapted to be flexed outwardly out of said recess into a non-obstructing position relative to said tube edge, to permit the tube to be inserted into or extracted from said slit by being slid axially into or out of said slit.

ERNEST A. FEUSTEL.
